TWO-WAY FIRE EXTINGUISHER LOCATOR SIGN

Roman Christman, Larry Christman, and Ricky Christman, all of 1516 N. 3rd St., St. Cloud, Minn.

Filed Oct. 24, 1974, Ser. No. 518,381

Term of patent 14 years

Int. Cl. D20—03

U.S. Cl. D96—12 R

FIG. 1

FIG. 2

FIG. 3

FIG. 1 is a top plan view of the two-way fire extinguisher locator sign showing our new design;

FIG. 2 is a side elevational view thereof, the opposite side being a mirror image of the side shown; and

FIG. 3 is a rear elevational view of FIG. 2.

The sign is shaded to indicate contrast.

We claim:

The ornamental design for a two-way fire extinguisher locator sign, substantially as shown and described.
